CLAIM

The ornamental design for a reel component, as shown and described.

DESCRIPTION

FIG. 1 is a front top perspective view of a reel component showing the new design;
FIG. 2 is a rear bottom perspective view thereof;
FIG. 3 is a rear elevational view thereof;
FIG. 4 is a front elevational view thereof;
FIG. 5 is a left elevational view thereof;
FIG. 6 is a right elevational view thereof.
FIG. 7 is a top plan view thereof; and,
FIG. 8 is a bottom plan view thereof.
The dash-dot broken lines in FIGS. 1-7 show portions of the reel component which form no part of the presently claimed design.
